UNITED STATES PATENT OFFICE.

MARTIN P. LUTHER, OF CHICAGO, ILLINOIS, ASSIGNOR TO SUPER-SAFETY SWITCH COMPANY, OF CHICAGO, ILLINOIS, A CORPORATION OF ILLINOIS.

ELECTRIC SWITCH.

Application filed November 23, 1921. Serial No. 517,213.

This invention relates to electric switches, and more particularly pertains to a novel and improved lock construction for use in connection therewith.

The lock construction of the present invention has been described briefly in my co-pending application filed November 23rd, 1921, Serial No. 517,211, and while I find its construction is peculiarly adapted to the switch described and claimed in said application, the lock is by no means limited to the adaptation there typified, but, for convenience it is here shown and described in connection with a rotary switch, like that described in said application.

The primary aim of this invention is to insure safety in the operation of electric switches, of either the rotary type or any other type to which the invention is adaptable, without material modification, and it is especially useful where the switch is installed in a cabinet and operable from without the same. Its object is, first, to prevent the opening of the cabinet while the switch is in course of movement from one extreme position to another, second, to lock the switch against movement in any direction when the cabinet is open, and third, to interlock the cover and switch whereby neither the switch nor cover can be moved without one or the other being in, what may be termed, a predetermined "safe" position.

It is further aimed to materially simplify the construction and reduce the cost of manufacture of switch locks. These and other aims of said invention will become apparent from the following detailed description and the claims.

In the drawings:

Figure 1 is a plan view of a switch cabinet with the cover open disclosing my improved lock.

Figure 2 is a longitudinal sectional view taken on line 2, 2, Figure 1, looking in the direction indicated by the arrows.

Figure 3 is a view similar to Figure 2, taken on dotted line 3, 3.

Figure 4 is an enlarged sectional view taken on line 4, 4, Figure 1, looking in the direction indicated by the arrows.

Figures 5 and 6, are views similar to Figures 2 and 3, illustrating modified forms of the invention.

Fig. 7 is an enlarged sectional view similar to Fig. 4 but showing the cover partially opened.

Referring more particularly to the drawings, 10 is a cabinet having sidewalls 11 and 12, endwalls 13 and a bottomwall 14; a cover 15 being hinged at 16, to the sidewall 11. This cabinet may or may not be constructed in accordance with that shown, described and claimed in my co-pending application, filed November 23, 1921, Serial No. 517,212, which serves to house the electrical switch shown in said application, although I do not desire to be confined to the use of such switch.

In Figure 1 of the drawings, I show a series of three corresponding switches 17, 17, 17, that are separably mounted upon a transverse shaft, 18, and are adapted to engage female connections 19, of a construction particularly described in the aforesaid co-pending application. Shaft 18 is journaled in suitable bearings 20 and 20^a in the sidewalls 11 and 12, respectively, and the switches 17 are revolved into and out of contact with the female connections that are seated in a suitable block X of porcelain or other non-conducting material.

The means employed to interlock the shaft 18 with the cover comprise disk 21, securely mounted upon and rotatable with shaft 18. This disk consists of two half sections 22 and 23 of different diameters, the ends of the section of the larger diameter affording shoulders 24 and 25, and provided with notches 26 and 27 diametrically opposite each other at substantially the point of meeting of the two sections. The shoulders and notches correspond to the extreme limits of motion of the switch, and are, preferably, 180 degrees apart, the switch, in the present instance, being constructed for movement through 180 degrees from open to closed position with relation to the terminals of the circuits controlled thereby.

The cover 15, carries a segmentally curved arm 28, fixedly secured thereto at 29, and operating through suitable openings 30 in the sidewall 11 of the cabinet as best shown in Figure 4. The free end of the segmental arm 28 is laterally bent at 31 to limit the distance to which the cover may be opened and to prevent the entire disengagement

with the disk. One edge of the segmental member 28 is provided with a notch 32, which when the cover is closed swings into alinement with the periphery of the smaller section 22, of the disk 23, and thus permits rotation of the switch in the direction indicated by the arrow *a*, in Figure 2, the shoulders 24 and 25, serving to limit the motion in either direction. However, when the cover is not fully closed, the notch 32 will be out of registration with the periphery of the section 22 of the said disk, and the body of said segmental member 28 will lie in one of the notches 26 or 27, of the disk, according to the position of the switch when the cover is opened.

In the event that it is desired to lock the switch temporarily in a full opened or closed position, a set screw 33 is provided in the larger section of said disk that engages the sidewall of the cabinet, or, if desired, engages positively in suitable openings therein to lock the switch in either position.

In the modified construction of the invention, shown, in Figures 5 and 6, the construction and mounting of the disk is the same, and its general operation is identical with that shown in Figures 1 to 4, inclusive, with the exception, that, in this instance, an arcuate-plate or link 34 is pivotally connected at 35 to the smaller section 22 of the disk, preferably midway between the notches 26 and 27, the free end of said arcuate member 34, being connected at 36, to a contractile helical spring 37 that has its free end anchored at 38, to the sidewall 11 of the cabinet. The purpose of this arrangement is that, in some instances, it is desired to maintain the switch manually closed at certain times, and to provide means for opening the switch when released by the operator and obviously while other means might be employed in lieu of that shown in Figures 5 and 6, I prefer to employ this modification in view of its simplicity, and, in view of its positive operation, because of the small amount of space it consumes. This will be apparent when it is seen from Figure 6, that the segmental member embraces the shaft 18 when the switch is closed, and at all times insures a practically rectilinear pull upon the spring 37.

While the structure described and illustrated is to be preferred, in view of its simplicity, and positive operation, it will of course be understood that I reserve the right to make minor changes in the details there-

of, which do not depart from the spirit of the invention and the scope of the claims.

What I claim as new is:

1. In combination, an electric switch controlling one or a plurality of circuits, a cabinet for the switch, a closure for said cabinet, and means operable by the closure for locking the switch in either of its positions of control when the closure is open.

2. In combination, an electric switch controlling one or a plurality of circuits, a cabinet for the switch, a closure for said cabinet, means operable by the closure for locking the switch in either of its positions of control when the closure is open, and means for preventing the closure being opened when the switch is between its extreme positions of motion.

3. In combination, a cabinet, a rotary electric switch therein controlling one or a plurality of circuits, means for locking the switch in either of its positions of control when the cabinet is open, and coacting means for preventing opening of the cabinet when the switch is on a cycle of motion.

4. In combination, an electric switch comprising rotatable circuit control members, a rotary shaft, upon which said members are mounted, a case for the switch, a cover therefor, a disk on one end of said shaft, having notches corresponding to the on and off positions of the switch, and means carried by the cover for engagement with said notches for locking the shaft when the cover is open.

5. In an electric switch a casing, a cover therefor, a rotatable shaft, a circuit closing device mounted on said shaft, a disc having two peripheral notches thereon mounted on the shaft, and means mounted on the cover cooperating with said disc whereby the switch is locked either in its on position or in its off position when the cover is open.

6. In an electric switch a casing, a cover therefor, a rotatable shaft, a circuit closing device mounted on said shaft, said device being rotatable through substantially 180 degrees from its on position to its off position, a disc having two peripheral notches mounted on said shaft, and means mounted on the cover cooperating with said disc whereby said switch is locked either in its on position or in its off position when the cover is open.

In witness whereof I hereunto set my hand this thirty-first day of October, 1921.

MARTIN P. LUTHER.
